UNITED STATES PATENT OFFICE.

KARL SCHACHTER, OF DORCHESTER, MASSACHUSETTS.

PERIODICAL HOLDER.

Application filed January 16, 1928. Serial No. 247,237.

This invention relates to improvements in periodical holders and one of the objects thereof is to provide a novel and convenient device which may be clamped around an intermediate portion of the periodical such as a newspaper to hold the sheets thereof together and to provide a convenient holder which will permit the turning of the pages.

A further object of the invention is to provide a device of the character specified with clamping members one or more of which are formed in telescoping sections with locking means operable upon relative longitudinal movement of one of said telescoping sections to retain the clamping members in clamped position upon the periodical, thereby preventing displacement or loss of the sheets of the periodical and also providing a convenient holder therefor.

20 A further object of the invention is to provide a periodical holder having clamping members comprising longitudinally adjustable sections whereby the clamping members may be adjusted to fit periodicals of 25 different widths.

20 A further object of the invention is to provide a periodical holder of the character specified with a handle secured to one of the clamping members and having means to 30 receive the free end of the other clamping member.

Another object of the invention is to provide means for releasably locking the free end of the telescopically adjustable member 35 in a handle which is secured to the other clamping member.

A further object of the invention is to provide a periodical holder of the character specified having a plurality of clamping 40 members each of which is formed in telescopically adjustable sections with means for clamping the sections of one of said members against longitudinal movement and providing means operable by relatively longitudinal movement of the other adjustable member to lock the free end of the clamping members together.

A further object of the invention is to provide a novel pivotal connection between 50 like ends of the clamping members which will also provide a hanger for supporting the clamping members with the periodical clamped thereby when not in use.

These and other features of the invention

will more fully appear from the following 55 description and the accompanying drawings and will be particularly pointed out in the claims.

A preferred embodiment of the invention is illustrated in the accompanying drawings 60 in which:

Fig. 1 is a perspective view of the periodical holder embracing the central portions of the sheet of a periodical such as a newspaper which is shown in unfolded position. 65

Fig. 2 is a view of the holder illustrated in Fig. 1 shown partly in longitudinal section with a periodical held between the clamping members thereof and also illustrating in dotted lines the manner in which the handle 70 may be moved longitudinally to release the otherwise free ends of the clamping members.

Fig. 3 is an enlarged detail view partly a vertical longitudinal section of the handle 75 portion and showing also the manner in which corresponding telescoping sections are respectively, permanently and releasably connected to the handle.

Fig. 4 is a smaller detail view of the construction illustrated in Fig. 3 showing the relative position of the handle and one of the telescoping members when released from the handle. 80

Fig. 5 is a side elevation of a preferred 85 form of combined hanger and pivotal connection for the clamping members.

Fig. 6 is a side elevation of the same.

Fig. 7 is a sectional view on lines 7—7 of Fig. 5. 90

The periodical holder illustrated in the accompanying drawings comprises two clamping members which are hinged together at one end and one or both of which is formed in telescoping sections with means 95 for releasably connecting the opposite ends together. The sections 1 and 2 of the clamping members are of tubular form and desirably of rectangular cross section and are connected together at one end by a combined pivotal connection and hanger 3. The clamping member 1 is provided with an extensible section 4 telescopically mounted therein and adapted to be secured in adjusted position by a suitable means such as a set-screw 5 mounted in the member 1 and abutting at its end against the member 4. The other tubular section 2 is likewise pro-

vided with a longitudinally movable section 6 which is telescopically mounted in the member 2. The free end of one of the telescoping members 4 or 6—which is illustrated in Fig. 3, as 6,—is fixedly secured by rivets 7 to the ferrule 8 of a suitable handle 9. The other telescopically mounted section 4 is adapted to enter the ferrule 8 upon relative longitudinal movement of the sections 4 and 6, so that when the end of the section 4 is introduced into the ferrule as illustrated in Fig. 3 the clamping members will be effectively locked together in clamping position in such a manner as to prevent displacement or loss of the sheets of the periodical which may be clamped between said clamping members.

Desirable releasing locking means are provided for preventing relative longitudinal movement of the telescoping sections 4 and 6. A convenient form of device for accomplishing this purpose may be provided by producing an indentation 10 in the ferrule 8 adapted to engage a complementary recess 11 in the end portion of the member 4.

Any suitable means may be provided for hinging the ends of the tubular sections together. A combined hanger and hinge is illustrated in detail in Figs. 5, 6 and 7. The construction thus shown comprises a wire bent into the form of a loop 3 having parallel reversely bent end sections 12 and 13 which pass through suitable sockets in the ends of the respective clamping members. In the preferred construction shown the tubular sections of the clamping members are provided with extensions 14 and 15 which are bent or otherwise formed to provide sockets having axes extending at right angles to the respective axes of the clamping members. The parallel reversely bent end portions 12 and 13 of the loop 3 pass through these sockets and are slightly upturned at the end to prevent disengagement therefrom. Adjacent overlapping portions of the loop 3 may, if desired, be soldered or brazed together as illustrated in Figs. 6 and 7 or may be secured together in any other well-known manner to increase the rigidity of the hinge construction. By virtue of this construction the clamping members 1 and 2 may be freely swung about the extensions 12 and 13 of the hanger to permit the clamping members 55 to be opened so that the periodical can be placed between them.

The operation of the device is illustrated in Fig. 1 in which the clamping members 1 and 2 lie upon opposite sides of the central fold of the newspaper 16 or other periodical with the telescoping sections 4 and 6 projecting beyond the lower edge of the periodical. The telescopically movable section 6 is fixedly secured to the ferrule 8 of the handle, while the telescopically mov-

able section 4 is adjustably secured within the tubular member 1 by the set-screw 5 so that the free end of the telescoping member projects a short distance beyond the lower edge of the periodical and when the periodical is placed between the clamping members the telescoping sections 4 and 6 are pinched together until the end of the section 4 is in alignment with the recess of the ferrule 8. The handle is then forced forward or towards the bottom edge of the periodical so that the end of the telescoping section 4 will enter said socket sufficiently to cause its recess 11 to be engaged by the indentation 10 in the ferrule thereby desirably locking the otherwise free end of the clamping members together with the periodical firmly clamped between said clamping members. The handle provides a convenient means to hold the paper while reading and to permit the turning of the pages thereof readily. When the reader has finished perusing the periodical it can be hung by the ring hanger 3 upon a suitable hook or nail upon the wall. When it is desired to remove the periodical from the holder it is merely necessary to depress the telescoping member 4 sufficiently to disengage the recess thereof from the indentation 10 of the ferrule and then to cause relative movement of said telescoping members 4 and 6 sufficiently to free the end of the member 4 from the ferrule, as illustrated in Fig. 4 whereupon the clamping members 1 and 2 may be separated and the periodical removed. The clamping members may be made of any suitable, preferably light, material and the tubular member may be any desired cross sectional form. The adjustable sections may be either in the form of bars or of light tubular members suitably mounted in the tubular members 1 and 2 as will be readily understood by those skilled in the art.

It is obvious that where periodicals such as newspapers are of a standard size, only one of the clamping members need be formed in telescoping sections. It will also be obvious that various other means may be devised for locking the clamping members in clamping position, and further that other means may be employed for pivotally connecting together the ends of the clamping members.

It will thereupon be understood that the particular embodiment of the invention disclosed herein is of an illustrative character and not restrictive in the scope or meaning of the following claims.

Having thus described the invention, what is claimed as new, and desired to be secured by Letters Patent, is:

1. A periodical holder comprising a pair of normally parallel clamping members each formed in telescoping sections, means pivot-

ally connecting adjacent sections of said clamping members at one end, and means releasably connecting the opposite free ends of said clamping members.

5 2. A periodical holder comprising a pair of normally parallel clamping means one of which is formed in telescoping sections, means pivotally connecting adjacent sections of said clamping members at one end and 10 means upon the opposite free end of one of said clamping members to receive the corresponding end of the other member upon relative longitudinal movement of said telescoping sections.

15 3. A periodical holder comprising a pair of normally parallel clamping members each formed in telescoping sections, means for locking the section of one of said telescoping members against longitudinal movement 20 and means upon the free end of one of said telescoping sections to engage the corresponding end of the other member upon relative longitudinal movement of said movable sections.

25 4. A periodical holder comprising a pair of normally parallel clamping members each formed in telescoping sections, means for locking the sections of one of said telescoping members against longitudinal movement, 30 means upon the free end of one of said telescoping sections to engage the corresponding end of the other member upon relative longitudinal movement of said movable sections, and releasable means for preventing relative 35 longitudinal movement of said movable section when thus engaged.

5. A periodical holder comprising a pair of normally parallel clamping members each formed in telescoping sections, means pivotally connecting adjacent sections of said clamping members at one end and a handle connected to the opposite end of one of said clamping members having a socket to receive the corresponding end of the other 45 clamping member upon relative longitudinal movement of said telescoping sections.

6. A periodical holder comprising tubular sections pivotally connected at one end and movable sections telescopically mounted in 50 the respective tubular sections, a handle fixedly secured to one of said movable sections having a socket to receive the end of the

other movable section upon relative longitudinal movement of said movable section.

7. A periodical holder comprising tubular 55 sections pivotally connected at one end and movable sections telescopically mounted in the respective tubular sections, a handle fixedly secured to one of said movable sections having a socket to receive the end of the 60 other movable section upon relative longitudinal movement of said movable section and engaging means upon said handle and the cooperating relatively movable section 65 operable releasably to lock said movable section to said handle.

8. A periodical holder comprising tubular sections pivotally connected at one end and movable sections telescopically mounted in the respective tubular sections, a handle fixedly secured to one of said movable sections having a socket to receive the end of the 70 other movable section upon relative longitudinal movement of said movable section and a set-screw in one of said tubular sections adapted to engage the movable section 75 which is telescopically mounted therein to lock said sections in adjusted position.

9. A periodical holder comprising a pair of normally parallel tubular clamping members each having an extension bent to present a socket having an axis perpendicular to the longitudinal axis of the clamping member and a wire loop having overlapping portions fixedly secured together and 80 reversely bent parallel extensions engaging the respective sockets in said tubular members and means for releasably locking the free 85 ends of said clamping members together.

10. A periodical holder comprising a pair of normally parallel clamping members each formed in telescoping sections comprising a tubular section having an extension bent to present a socket having an axis perpendicular to the longitudinal axis of the clamping members and a loop having overlapping 90 reversely bent parallel sections engaging the respective sockets in said tubular members and means for releasably locking the free 95 ends of the relatively movable telescoping sections together.

In testimony whereof, I have signed my name to this specification.

KARL SCHACHTER.
